UNITED STATES PATENT OFFICE.

LUCIAN MANTELL, OF NEW YORK, N. Y.

SPRINKLER.

Application filed July 9, 1921. Serial No. 483,542.

One of the objects of the invention is to provide a sprinkler comprising a hollow body having nozzles radiating therefrom and constructed with a passage-way running therethrough which may be telescoped upon any existing projection in a room such as gas pipe or an electric conduit and become an ornamental part thereof.

Another object of the invention is to provide a rotatable sprinkler comprising a hollow body having nozzles with vanes on the interior thereof said rotatable hollow body being actuated by the jet of incoming water to rotate said body.

15 A still further object of the invention is the provision of a rotatable sprinkler having a plurality of swivel joints in different planes with single means external to the sprinkler for simultaneously adjusting the 20 tightness of the several joints.

With the above and other objects in view, my invention consists in the improved sprinkler illustrated in the accompanying drawings, described in the following specification, and particularly claimed, and in such variations and modifications thereof as will be obvious to those skilled in the art to which my invention relates.

25 In the drawings accompanying and forming a part of this specification, and wherein the preferred embodiment of my invention is illustrated:

30 Figure 1 is a sectional elevation showing one form of my improved sprinkler.

35 Figure 2 is a perspective view of the same.

Figure 3 is a cross section taken along the lines 3—3 of Figure 1.

40 Figure 4 is a slightly modified form of my invention shown in cross section.

Referring now to Figure 1 which shows a form of my improved sprinkler, the base 20 is provided with the externally threaded annular flange 21 which engages the dome-shaped casing 22 having its lower end open and slightly rabbeted as at 23 forming an annular joint for the reception of the hollow globular sprinkler head 24. Said sprinkler head is adjustably attached at its lower end to a hollow threaded conduit 25 which passes through the dome-shaped portion and through the support 20. To the outer end of said conduit is threadedly secured the convex bearing member 26 adapted to rotate within the concave depression 27 formed in the upper face of the support

20 cooperating therewith to form a swivel joint. Secured externally to the outer walls of said conduit are the vanes 28 which lie in the path of the incoming jet of water 60 from the tangentially arranged pipe 29, as best shown in Figure 3.

The globe-shaped sprinkler head 24 is provided with a number of radially extending nozzles 30 arranged in several planes 65 about the surface thereof each provided with a flat slot shaped opening 31 preferably arranged in a vertical plane. The function of the slots is to permit the water to issue therefrom in fan shaped jets. The 70 surface of the sprinkler head is provided also, in the spaces between the nozzles with vertically and horizontally arranged slots 40 and 41, and with various small apertures 42, said slots and apertures producing jets 75 of various shapes which commingle with the fan-like jets from the nozzles; ensuring a thorough distribution of the water on all sides of the room to be sprinkled when the sprinkler head is rotated. The globular 80 sprinkler head 24 is made in two parts threadedly connected together at 32 to facilitate the practical manufacture of the same. The lower end of the conduit 25 is preferably provided with a kerf 33 which is adapted to receive a tool by means of which the conduit 25 is held stationary while the tightness of the joints 27 and 23 is regulated by turning the globular head 85 relative to the conduit.

In the modification of the sprinkler shown in Figure 4 the pipe 38 represents a fixed support such as the pipe of a gas jet or electric fixture which may be found already installed in the room in which it is desired to 90 place the sprinkler device when the latter is used as an adjunct to a fire extinguishing system. When mounted upon said pipe or conduit the sprinkler head becomes an ornamental portion of the same and its function 100 is not readily guessed from mere casual inspection. In the modification shown in both Figures 1 and 4, the base 20 is shown as securable to any suitable support by means of bolts or screws passing through the apertures 39. It is well within the scope of the invention, however, to modify the form of the base and the means of securing the same to suit the peculiar exigency in each case.

Aside from its particular use as a fire extinguishing apparatus the sprinkler is readily adaptable to use in any of the fields with

utility in which a sprinkling device is applicable. The modification as shown in Figure 1 is especially adapted to use as a lawn sprinkler as well as a fire extinguishing apparatus, as it may be placed in inverted position upon the ground and a stake of smaller diameter than the internal diameter of the conduit 25 pushed through the conduit 25 and into the ground securing the 10 sprinkler in place and preventing its overturn when the hose to which it would be attached is moved.

While I have above described what I have found to be a very practical embodiment of 15 my invention, it is nevertheless to be understood that the sprinkler may also be exemplified in numerous other alternative constructions and I accordingly reserve the right of adopting all such legitimate changes as may 20 be fairly embodied within the spirit and scope of the invention as claimed.

Having described my invention what I claim as new and desire to secure by Letters Patent, is:—

25 1. A sprinkler comprising a hollow base, a hollow shaft journalled in said base and extending therethrough, a perforate jacket surrounding said shaft and secured thereto forming with the outer wall of said shaft a 30 water chamber communicating with said base, vanes within the hollow base and secured to said shaft, a water inlet communicating with said base to direct a jet of water against said vanes, and an end-thrust bearing 35 on said shaft engaging the side of said base opposite said perforate jacket.

2. A sprinkler comprising a hollow base having an open end, a hollow shaft journalled in said base and passing therethrough, 40 a perforate jacket surrounding said shaft and secured thereto at one end forming with

the outer wall of said shaft a water chamber, the upper end of said jacket being open and registering with the open end of said hollow base, means secured to said shaft for 45 rotating the same, a water inlet communicating with said hollow base, and an end-thrust bearing on said shaft engaging the side of said base opposite said perforate jacket. 50

3. In a sprinkler, a support, a bearing in said support, a shaft journalled in said bearing, said support being provided with a threaded annular flange a hollow bushing engaging said flange at one end and open at 55 the other forming with said support a hollow chamber, a perforate jacket surrounding said shaft and in registry with the open end of said bushing making a swivel joint therewith, vanes in said hollow bushing secured 60 to said shaft and a water inlet communicating through said bushing with said jacket.

4. A sprinkler comprising a support, a bushing secured to one side of said support 65 having an end open in a plane normal to the longitudinal axis of said support, a bearing on the other side of said support, a shaft journalled in the bearing forming a joint therewith and passing through the open end of said bushing, a perforate sprinkler head surrounding said shaft and adjustably threaded thereon at its outer end, the inner end of said sprinkler head abutting the open end of said bushing to form a joint therewith, and means for holding said shaft stationary while the sprinkler head is screwed 70 more or less closely thereon for simultaneously adjusting the play of said joint. 75

In testimony whereof I have hereunto set 80 my hand.

LUCIAN MANTELL.
